(57) **CLAIM**

The ornamental design for bottle, as shown and described herein.

DESCRIPTION

FIG. 1 is a top perspective view of a first embodiment of a bottle embodying the new design.

FIG. 2 is a bottom perspective view thereof.

FIG. 3 is a front view thereof.

FIG. 4 is a rear view thereof.

FIG. 5 is a first side view thereof.

FIG. 6 is a second side view thereof.

FIG. 7 is a top view thereof.

FIG. 8 is a bottom view thereof.

FIG. 9 is an exploded perspective view thereof.

FIG. 10 is an exploded front view thereof.

FIG. 11 is a top perspective view of a second embodiment of a bottle embodying the new design.

FIG. 12 is a bottom perspective view thereof.

FIG. 13 is a front view thereof.

FIG. 14 is a rear view thereof.

FIG. 15 is a first side view thereof.

FIG. 16 is a second side view thereof.

FIG. 17 is a top view thereof.

FIG. 18 is a bottom view thereof.

FIG. 19 is an exploded perspective view thereof.

FIG. 20 is an exploded front view thereof.

FIG. 21 is a top perspective view of a third embodiment of a bottle embodying the new design.

FIG. 22 is a bottom perspective view thereof.

FIG. 23 is a front view thereof.

FIG. 24 is a rear view thereof.

FIG. 25 is a first side view thereof.

FIG. 26 is a second side view thereof.

FIG. 27 is a top view thereof.

FIG. 28 is a bottom view thereof.

FIG. 29 is an exploded perspective view thereof.

FIG. 30 is an exploded front view thereof.

(Continued)

FIG. 31 is a top perspective view of a fourth embodiment of a bottle embodying the new design.
 FIG. 32 is a bottom perspective view thereof.
 FIG. 33 is a front view thereof.
 FIG. 34 is a rear view thereof.
 FIG. 35 is a first side view thereof.
 FIG. 36 is a second side view thereof.
 FIG. 37 is a top view thereof.
 FIG. 38 is a bottom view thereof.
 FIG. 39 is an exploded perspective view thereof; and,
 FIG. 40 is an exploded front view thereof.
 The broken lines on the middle of the body of the bottle depict symbolic break lines. Any appearance of the bottle between the break lines form no part of the claimed design. The remaining broken lines in the drawings depict environmental subject matter and form no part of the claimed design.
